CARD FILING DEVICE

William Harvey Seeley, Toronto, Ontario, Canada

Application August 31, 1936, Serial No. 98,728
In Canada March 10, 1936

2 Claims. (Cl. 45—3)

The invention relates to improvements in card filing devices, as described in the present specification and illustrated in the accompanying drawings which forms a part of the same.

5 The invention consists essentially in mounting a series of cards on rotatable wheels and enclosing the wheels in cabinets, as more particularly pointed out in the claims for novelty following a description containing an explanation in detail 10 of an acceptable form of the invention.

The objects of the invention are to devise an improved filing construction which will retain a large number of cards or the like, relative to its size, in a restricted area upon a suitable support, 15 easily and readily accessible; to construct a filing device from which the cards can be easily removed and placed in proper position without disturbing the remainder; to furnish a filing device in which the cards will be immediately available, 20 and may be shifted wherever it is more convenient for use; to facilitate posting, saving time and labor, and eliminating errors to a great extent in checking, mailing lists and other operations; to construct a filing device in which the cards may 25 be properly indexed, in clear view of the operator, colored if desired for speeding classification and reference; and generally to provide an enclosed filing device that will be dust-proof, simple and reasonable in cost of construction and efficient 30 for its particular purposes.

In the drawing:

Figure 1 is a side elevation showing a type of cabinet having a pull out cover.

Figure 2 is a cross sectional view showing the 35 method of mounting the file within the cabinet.

Figure 3 is a sectional plan view showing the method of mounting and securing the file within the cabinet.

Figure 4 is a fragmentary detail showing the 40 method of securing the tension spring to the pivoted frame.

Figure 5 is an enlarged fragmentary detail showing the pivoted frame journals.

Figure 6 is an enlarged fragmentary detail 45 showing the pivoted frame locking device.

Like numerals of reference indicate corresponding parts in the various figures.

Referring to the drawing, the card index as indicated by the numeral 25 is in the form of a 50 rotatable wheel-like member, rotatably mounted on a supporting shaft 26, suitably enclosed in a cabinet 27, and may comprise a single or a plurality of units, depending on the capacity and the type desired.

55 The cabinet as shown is of the desk-type hav-

ing a flat top 45, and pull-out type unit cover 46. The card file or files, as the case may be, are rotatably mounted on the supporting shaft 26, fixed in bearings 36 of the split or solid type. The supporting shaft 26 which may be rotatably or 5 fixedly secured in the bearings 36 is carried by the pivoted supporting frame 47, which consists of two suitably spaced side members 48 being held together by the distance pieces or tie rods 49, and this pivoted frame 47 is pivotally journaled 10 on the stub shafts 50 formed with the collars 51 and flanges 52, which are securely bolted to the cross walls or framework of the cabinet.

In order that the file may be elevated to convenient height when posting, etc., and that the 15 same may completely disappear into the lower unit when not in use, to allow the operator a clear desk, a suitable handle 53 and position locking means 54 is provided. The handle 53 is securely fixed in the pad 55 secured to the end of 20 the pivoted supporting frame 47, and is adapted to extend outwardly through the end wall 56 of the cabinet, the end wall having the radially formed slot 57 through which the handle 53 protrudes to within the operator's reach. The position locking means 54, which comprises a pointed 25 spindle 58, terminating in a handgrip 59, suitably supported in the bracket 60 which is secured on the outer side of the cabinet end wall 56 in convenient relation to the handle 53, and 30 this pointed spindle 58 is adapted to engage holes 61 suitably spaced in the pad 62 securely fixed to the pivoted supporting frame 47. To prevent the spindle from working free or out of the pad 62, a tension spring 63 is provided, 35 securely held in position within the bore 64 of the bracket 60 by the pinned washer 65.

To relieve the dead weight of the file, etc., when raising or lowering to various positions, a balance is provided in the form of a helical tension spring 40 66, its coiled end being suitably housed in the casting 67, the open end 68 being attached to the front tie rod 49.

What I claim is:

1. In a filing device of the character described, 45 a portable cabinet, a frame pivotally mounted in said cabinet, a transverse shaft secured to said frame, a rotary member mounted on said shaft and having a substantially circular channel adapted to receive a plurality of cards, means 50 for moving said frame about its pivot and thereby raising and lowering said rotary member and means for locking said frame at the required elevation.

2. In a filing device of the character described, 55

a portable cabinet, a frame pivotally mounted in said cabinet, a transverse shaft secured to said frame, a rotary member rotatably mounted on said shaft and having a peripheral channel adapted to receive a plurality of cards in a substantially radial position, means for retaining

said cards within the channel and means for moving said frame about its pivot and thereby raising and lowering said rotary member, and means for locking said frame at the required elevation.

WILLIAM HARVEY SEELEY.
